UNITED STATES PATENT OFFICE

ALBERT C. FRITZ, OF EVERGREEN PARK, ILLINOIS

DESIGN FOR A BURIAL VAULT

Application filed April 6, 1933. Serial No. 47,712. Term of patent 7 years.

To all whom it may concern:

Be it known that I, ALBERT C. FRITZ, a citizen of the United States, residing at Evergreen Park, in the county of Cook and State of Illinois, have invented a new, original, and ornamental Design for a Burial Vault, of which the following is a specification, reference being had to the accompanying drawing, in which the figure is a perspective view of a burial vault, showing my new design.

I claim:

The ornamental design for a burial vault, as shown.

In testimony whereof I affix my signature.

ALBERT C. FRITZ.
